(57) CLAIM

The ornamental design for a ball marker holder, as shown and described.

DESCRIPTION

FIG. 1 is a top, front, and left side perspective view of a ball marker holder according to our new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a right side elevation view thereof;

FIG. 7 is a left side elevation view thereof; and,

FIG. 8 is a top, front, and right side perspective view thereof. The dot-dash broken lines represent boundaries of the claimed design and form no part of the claimed design. The dash-dot broken lines depict portions of the ball marker holder that form no part of the claimed design.
